UNITED STATES PATENT OFFICE.

JAMES E. HUMPHREY, OF ABERDEEN, SOUTH DAKOTA.

DINNER-PAIL.

SPECIFICATION forming part of Letters Patent No. 784,215, dated March 7, 1905.

Application filed July 9, 1903. Serial No. 164,773.

To all whom it may concern:

Be it known that I, JAMES E. HUMPHREY, a citizen of the United States, residing at Aberdeen, in the county of Brown and State of 5 South Dakota, have invented certain new and useful Improvements in Dinner-Pails; and I do hereby declare the following to be a full, clear, and exact description of the invention, such as will enable others skilled in the art to 10 which it appertains to make and use the same.

My invention relates to so-called "self-heating" dinner-pails, or dinner-pails having heating attachments, and is especially intended for improvement on self-heating dinner-pails 15 of the character disclosed in the claims in Letters Patent of the United States No. 646,185, issued to Harvey L. and Charles Marlett, of date March 27, 1900.

The invention consists of the novel construction and combinations of parts hereinafter described, and defined in the claim.

The invention is illustrated in the accompanying drawings, wherein like characters indicate like parts through the said views.

25 Figure 1 is a view in central elevation showing a dinner-pail constructed and equipped in accordance with my invention, some parts of the same being broken away and some being sectioned; and Fig. 2 is a horizontal section 30 taken on the line X² X² of Fig. 1.

In this preferred construction of a pail the body thereof is of rectangular form and is provided with a false bottom 2, between which and the bottom proper of the body 1 is formed 35 a horizontally-extended combustion-chamber 3. At one end the combustion-chamber 3 is open, but is adapted to be closed by a sliding door 4, mounted in suitable guides 5 on one end of the pail.

40 The numeral 6 indicates a lamp, such as an alcohol-lamp, which is loosely placed within the combustion-chamber 3 as far as possible from the open end thereof. Above the space thus occupied by the lamp 6 the false bottom

45 2 is cut away, as shown at 7. The main compartment of the body 1—that is, that portion above the false bottom 2—is filled by a removable open-ended box 8 and by a removable coffee-can 9, which parts 8 and 9 are, as shown, 50 both rectangular. The removable coffee-can

9 rests on the false bottom 2 with the greater portion of its own bottom directly exposed to the flames from the lamp 6 through the opening 7 of the said false bottom. A draft-flue 10 is secured at its lower end to the several portions of the bottom of the can 9 and rises vertically therethrough, with its upper end projecting above the top of said can. The upper end of the can 9 is adapted to be closed by a removable cover 11, which is 60 provided with a simple perforation which quite loosely fits around the upper end of the flue 10.

The pail-body 1 is provided with a removable cover 12, which is provided with a threaded sleeve 13, which when the cover 12 is placed in working position loosely telescopes over the projecting upper end of the flue 10. The open upper end of this sleeve 13 is adapted to be closed by a threaded cap 14. 70 The pail-body 1, as shown, is provided with an ordinary bail 15, and the cover 12 is shown as provided with an ordinary tin cup 16 and cup-holding sleeve 17.

Numeral 18 indicates a sheet of asbestos 75 which is placed between the false bottom 2 and the bottom of the box 8 to prevent excessive heating of the solid articles of food which would usually be placed in the said box.

When the coffee or other liquid contained 80 within the can 9 is to be warmed, the lamp 6 is of course lighted, and to give a sufficient supply of air to support combustion within the chamber 3 the door 4 must of course be open more or less. The hot flames strike the bottom of the can 9 and then pass up through the flue 10 and rapidly heat the liquid contained in said can. The pail-cover 12 may be left in position on the body 1 while the lamp is burning; but the cap 14 must of course be removed at such time. In fact, by placing the cap 14 on the neck 13 the lamp may be snuffed out by cutting off the draft through the flue 10.

With the flue formed as part of the removable can 9 both of the parts may be removed together, and thus easily cleaned. To obtain the greatest heating efficiency, the flue must be passed centrally through the can, and for convenience in use the said can should of 100

course be removable from the body of the pail. These conditions are all met in my improved pail above described.

What I claim, and desire to secure by Letters Patent of the United States, is as follows:

In a self-heating dinner-pail, the combination with the body 1 having the false bottom 2 perforated at 7 and formed below said false bottom with the combustion-chamber 3 open ¹⁵ at one end, of the lamp 6 insertible into said combustion-chamber below said perforation 7, the can 9 resting on said false bottom over said perforation 7 and provided with the flue ²⁰ 10 passing vertically therethrough and terminating above the top thereof, and the pail-cover 12, having the sleeve 13 which telescopes over the projecting upper end of said flue 10 and is provided with the removable cap 14, substantially as described.

In testimony whereof I affix my signature in presence of two witnesses.

JAMES E. HUMPHREY.
